ELECTRIC SWITCH

Johann G. Peterson, West Hartford, Conn.

Application May 3, 1934, Serial No. 723,718

15 Claims. (Cl. 200—11)

My invention relates to electric switches. It has for its object to provide an improved electric switch, and, more particularly, an improved snap switch of the type shown in my prior patent, No. 1,894,002, and adapted to control a plurality of circuits such, for example, as the circuits of a heating pad or the like. A further object of my invention is to provide an improved switch of this character which is markedly more compact than previous switches of this type, and thereby especially adapted to use as a through switch connected in the conductors of a heating pad, all in such manner as to reduce substantially the annoyance or discomfort of a user inadvertently rolling upon the through switch when the heating pad is in use. Further objects of my invention are to provide improved switch unit and through switch constructions which, while having the advantages aforesaid and also being entirely safe, and very convenient in operation, are also adapted to be substantially more economically produced than previous switches of this type. These and other objects and advantages of my improved construction will, however, hereinafter more fully appear.

In the accompanying drawing, I have shown for purposes of illustration, one embodiment which my invention may assume in practice.

In the drawing:

Figure 1 is a plan view of this form of my improved switch in a through switch casing, one of the casing members being removed to facilitate illustration;

Figure 2 is a corresponding view of the opposite side of the switch;

Figure 3 is a plan view of one of the casing members, the switch unit being removed therefrom;

Figure 4 is a sectional view on line 4—4 of Figure 1;

Figure 5 is a sectional view on line 5—5 of Figure 1;

Figure 6 is a plan view of the switch unit removed from the casing, one of the insulating plates also being removed to facilitate illustration;

Figure 7 is a side elevation of the mechanism shown in Figure 6 when viewed from the left-hand side of that figure, the actuating member being shown as centrally disposed;

Figure 8 is a plan view of the construction shown in Figure 6 with the swinging elements also lifted off to facilitate illustration;

Figure 9 is a view similar to Figure 8, but show-

ing the inside face of the cooperating insulating plate shown in Fig. 1 but removed in Figs. 6—8;

Figure 10 is a series of detail perspective views of the swinging elements of the switch;

Figure 11 is a transverse sectional view through the switch actuating parts, showing the movable elements thereof in one position, and

Figure 12 is a view similar to Figure 11, but showing the parts in another position.

In this illustrative construction, I have shown 10 my improved switch enclosed in cooperating casing members 1 and 2 of a usual longitudinally divided through switch type and having my improved switch mechanism therebetween and operable by an actuating member 3 movable in a 15 slot 4 longitudinally of the casing members from the "off" position of the same illustrated in Figure 1, in the same direction into the several "on" positions indicated in dotted lines in that figure, and then reversely movable to return to the full 20 line position illustrated; the switch mechanism herein including a unit having spaced insulating plates 5 and 6 connected by connecting members 7 at their ends and, respectively, carrying a terminal plate 8 and through connection 9, and a 25 plurality of terminal plates 10 and 11, each provided with usual binding screws, while the switch mechanism between the plates is improved as hereinafter more fully appears.

Referring more particularly to this switch 30 mechanism, it will be noted that herein the terminal 11 is connected through a rivet 12 with one of a pair of oppositely extending extensions 13 similarly riveted to the plate 6 and formed on one extremity of a metal conducting plate 14 35 having an aperture 15 therein adjacent one edge of the insulating plates 5 and 6 and in which and registering apertures in the latter plates the pivot pin of the switch, herein a stud 16, is disposed in such manner as to produce a very compact 40 construction as will hereinafter appear. Herein also this plate 14 is provided with a narrow inclined spring portion 17 extending toward the opposite edge of the plates 5, 6 and having an elongated end portion 18, substantially midway 45 between the plate edges, extending to opposite sides of the portion 17 and provided with a series of apertures 19 therein, herein four in number. As shown, each of these apertures 19 has beveled walls 20 and the apertures are disposed in an arc 50 struck from the stud 16 as an axis, as clearly appears in Figure 8. The portion 18 further is normally disposed in elevated position spaced above the insulating plate 6, as shown in Figure 5. Cooperating with the series of cams thus pro- 55

vided by the apertures 18, is also a movable cam carrying member, herein in the form of a member 21, pivoted on the stud 16 and having a single depending and preferably rounded or peaked projection 22 on the under side of its inner extremity, which is adapted to be received in the several apertures 18 as the member 21 is moved about its pivot on the stud 16 upon actuation of the pivoted actuating member 3.

Referring more particularly to the latter, it will be noted that the body or shank 23 of this member 3, herein of metal, is also provided with an aperture in its inner end registering with the aperture 18 and receiving the stud 16 so that the actuating member 3 is freely movable with the member 21 about this stud as a pivot. Moreover, it will be noted that the member 21 is provided with a vertical end portion 24 at right angles to the body portion thereof carrying the projection 22 and at the opposite end thereof from the latter, and also with a top portion 25 parallel to the body portion, but shorter than the latter and herein spaced from the adjacent insulating plate 5 by a metal washer 28. Herein also, both the body of member 21 and this portion 25 are provided with registering apertures 26 through which the stud 16 also extends. Also, it will be noted that the portion 24 is provided with an opening 27, herein of substantially rectangular form, through which the adjacent extremity 28 of the actuating member body 23 extends, while adjacent shoulders 28' engage the inner edges of the opening 27, in such manner that, when the actuating member 3 is moved about its pivot on the stud 16, the member 21 is caused to be swung therewith.

Operatively associated with the actuating means described is also improved contact means movable therewith. Herein, this contact means comprises a plurality of separate contact members 38 and 39 of identic construction but oppositely disposed, one above and the other below the shank 23 of the actuating member 3. As shown, each of these contact members is also provided with an aperture 31 near the non-contact carrying end thereof and through which the stud 16 is extended, while each of the same is also provided with a shouldered projection 32 on its adjacent extremity also extending through the opening 27 in the member 21. Also, it will be observed that these contact members extend outward along the shank 23 of the actuating member 3 and between the body of the member 21 and this shank in the case of the member 38, and 55 between the portion 25 on the member 21 and the shank 23 in the case of the member 29. Moreover, it will be noted that each is provided with an outwardly deflected or inclined contact carrying portion 33, carrying a contact 34 on the member 28, and an oppositely disposed contact 35 on the member 38, both of which contacts are herein disposed and movable in a narrow arc between the portion 18 on the member 16 and the actuating end of the actuating member 3 and also within and closely adjacent the edges of the insulating plates 5 and 6.

Cooperating with these movable contacts 34 and 35 are also improved stationary contacts carried on the insulating plates 5 and 6. Herein, when the actuating member 3 is in its "off" position, illustrated in Figures 1, 2, and 6, neither contact 34 nor 35 will, of course, engage a cooperating stationary contact. However, when the member 3 is moved down therefrom to the first adjacent dotted line position shown in Figure 1,

the movable contact 35 will engage a stationary contact 36 on the plate 6, herein in the form of a rivet connecting the terminal 10 to the plate 6. Further, when moved from this position down into the next, or second, dotted line position, shown in Figure 1, the other contact 34 will engage a similar stationary contact 37 on the plate 5, herein spaced from the contact 36 and also comprising a rivet but connecting the terminal plate 8 to the plate 5. When moved still further down into the bottom dotted line position shown in Figure 1, the contact 34 will engage a like contact rivet 38 while the contact 35 will engage a like contact rivet 39, these two stationary contacts 38, 39 being on the plates 5 and 6, respectively, and being simultaneously engaged, whereas the contacts 36 and 37 are alternately engaged. Thus, with current supplied from the terminal plate 11 through the rivet 12 to the plate 14 and through the latter and the associated metal parts to the contacts 38 and 39, it will be evident that current will be distributed in such manner that a pad having a through connection connected to the binding posts on the terminals 8, 10, and 11, will be successively connected for low, medium or high heating as the actuating member 3 moves downward through the three dotted positions indicated in Figure 1.

As regards the through connection 8, it will also be noted that herein the same is disposed on the outer face of the insulating plate 5 and between a protruding end of the stud 16 and the edge of the plate 5 which is remote from the actuating member 3. Further, it will also be noted that the portion of this through connection 35 adjacent the stud is quite narrow, in such manner as to enable it to be adequately spaced from the stud, while it will also be noted that the outer edge of this narrow portion is spaced from the outer edge of the insulating plate. The opposite ends of this member 8, are, however, enlarged and carry usual binding posts at their extremities, while between these binding posts and the narrow portion mentioned, rivets 38' are provided, riveting the through connection to the insulating plate; the inner ends of these rivets herein also being amply spaced from the portion 25 on the member 21 in all positions of the latter.

In connection with the casing, it will be noted that the upper casing member 2 is substantially of the longitudinal and transverse ribbed construction shown in my prior patent mentioned, save that the aperture 40 for receiving the end of the stud 16 is displaced substantially at one side of the longitudinal axis of the casing, as distinguished from being closely adjacent that axis, as in my prior construction. It will also be understood that the casing 1 is of substantially identic construction with the casing 2 save that, instead of the single transverse rib 41 on casing 1, which is engageable with the lower right hand corner of the insulating base 5 (Figure 1) where there is no binding screw, two such ribs are provided on casing 2 to engage the two like and diagonally opposite corners on plate 6 shown in Figure 2, all in such manner as to locate the unit in position while preventing incorrect assembly thereof in the casing. Both casing members, as previously described, are also provided with upstanding members 42 at the ends of their longitudinal extending rib and are connectible in a usual manner by screws 43 receivable in these portions 42, while the latter portions also function to locate the switch unit in position, as ill-

lustrated in Figures 1 and 2, in a well known manner.

Referring to the operation of the switch mechanism, it will be evident that in each of the various positions of the member 3, the projection 22 will be disposed in an aperture 19, as shown in Figure 12; the spring portion 18 then being raised and spaced from the insulating plate 6 as shown in that figure, which, for example, illustrates the parts in the position which they would occupy in the first dotted position corresponding to low heat. While the parts will be held in this position due to the resiliency of the plate 18, it will be evident that when the member 3 is moved to swing the member 21 and projection 22 about the stud 16, the projection 22 will ride up the inclined side 20 of the aperture 19 then occupied and force the spring plate 18 down as shown in Figure 11. As a result of the lateral pressure on the actuating member and the inclined side 20, the pointed end of the projection 22 will also be forced over the space between the apertures so that the projection 22 will seat in the next aperture 19 as the plate 18 again moves up. This, since the contacts 34 and 35 must move with the member 21 and the actuating member 3, results in a quick or snap movement of these contacts from one position into another. Thus, as the member 3 is moved through the positions illustrated in Figure 1, the contacts 34 and 35 will both be simultaneously thrown with a snap action following each actuation of the member 3, the contact 35 engaging first the contact 36 and breaking contact therewith before the contact 34 engages the contact 37, and the contact 34 breaking contact with the contact 37 before both contacts 34 and 35 simultaneously engage contacts 38 and 39.

As a result of my improved construction, while obtaining a safe and effective switch of the general type described and claimed in my previous Patent No. 1,894,002, it has been made possible to utilize only a single spring cam plate and a single movable cam cooperating therewith and a much more simple structure of contacts. Further, through the use of my improved, more compact mechanism having the stud 16 and parts 18 and 21, etc. located as described, it is made possible to reduce the size of the switch unit very substantially, approximately 20%, and similarly substantially reduce the necessary size of the casing members enclosing the switch unit. As a result of this construction, it is also made possible to reduce the cost of the switches by from approximately 20% to 25%, this reduction in cost being due not only to the improved and simplified switch mechanism structure and to the smaller size of the switch unit, but also to an even larger extent due to the smaller size of the casing which may be used in connection with the latter. These and other advantages of my improved construction will, however, be clearly apparent to those skilled in the art.

While I have, in this application, specifically described one embodiment which my invention may assume in practice, it will be understood that this form is shown for illustrative purposes, and that the structure may be modified and embodied in other forms without departing from its spirit or the scope of the appended claims.

What I claim as new and desire to secure by Letters Patent is:

1. In an electric switch, a pivoted actuating lever, snap actuating means actuated by said lever comprising cooperating resilient and swinging

cam elements both external of the confines of said lever and both disposed on the same side of said lever, and stationary and movable contact means including movable contact means actuated by said snap actuating means, said snap actuating means and movable contact means being disposed between the pivot for said lever and the free end of said lever in concentric arcs within the zone of a limited swing of said lever. 5

2. In an electric switch, a pivoted actuating lever, snap actuating means actuated thereby comprising cooperating resilient and swinging cam elements both disposed externally of the confines of said lever and between the pivot for said lever and the free end of said lever, and contact 15 means comprising a series of stationary contacts and a pair of cooperating movable contacts movable relative to said lever and actuated in unison by said snap actuating means and disposed between the latter and the free end of said lever. 20

3. In an electric switch, a pivoted actuating lever, contact means including a movable contact at one side of said lever and between the pivot and the free end of the lever and movable with said lever, and snap actuating means for 25 said contact actuated upon lever movement and disposed between the pivot and the free end of said lever upon the opposite side of said contact from said lever comprising a resilient member having spaced cam means and co-operating 30 swinging cam means movable progressively thereover as said lever swings.

4. In an electric switch, a pivoted actuating lever, a series of resiliently mounted cams disposed around the axis thereof between the lever 35 pivot and the free end thereof, a cooperating actuating cam movable with said lever, and contact means including a resiliently mounted contact member disposed between the pivot of said lever and the free end thereof and actuated to move about the pivot of said lever upon actuation of said lever and also movable relative to said lever as the latter moves about its pivot, said series of cams being carried on a spring plate on the opposite side of said movable contact member from said lever and movable toward and from said actuating lever upon movement thereof. 45

5. In an electric switch, a base, a pivoted actuating lever pivoted adjacent one edge thereof and having one end projecting beyond the opposite edge thereof, stationary and movable contact means along the latter edge of said base, and snap actuating means for the movable contact means actuated by said lever and disposed 50 between said pivot and said contact means and comprising a series of cams and a pivoted member for operating said movable contact means from said lever and having a cam cooperating with said series of cams. 55

6. In an electric switch, a base, a pivoted actuating lever thereon, a spring plate having a portion thereof normally spaced from said base and between the latter and said lever and having a plurality of cam means on said portion disposed 65 around said pivot, cooperating cam means movable in unison with said actuating lever and between said plate and lever, and cooperating movable and stationary contacts on said lever and base, said plate having its spaced portion movable toward and from said base between the latter and said lever as said actuating lever moves from one position to another. 70

7. A switch unit for through switches comprising an elongated insulating member receivable 75

- in a through switch casing, an actuating member pivoted on said insulating member substantially midway between the ends of the latter and adjacent one lateral edge thereof and having an operating end projecting from and movable along the opposite edge thereof, movable contact means movable by said actuating member along and adjacent said opposite edge and also movable relative to said actuating member, 5 stationary contacts along and adjacent said opposite edge, and snap actuating means for said movable contact means between said stationary contacts and the member pivot and actuated upon movement of said actuating member.
15. In a switch, a plurality of elongated spaced insulating plates, an actuating member pivoted therebetween substantially midway between the ends thereof and adjacent one lateral edge thereof and having an operating end projecting from 20 the opposite edge thereof, contacts adjacent said opposite edge, and snap actuating means actuated by said actuating member, said contacts comprising stationary contacts on different plates and movable contacts having an operative connection with said snap actuating means and alternately and then simultaneously, engaging 25 stationary contacts on different plates.
30. Movable switch mechanism for an electric switch comprising a holder member movable about a pivot and having an end aperture therein, a lever movable about said pivot and projecting into said aperture and interlocked with said holder for conjoint movement therewith, and contact members above and below said lever 35 also movable about said pivot and having portions projecting into said aperture and thereby interlocked with said lever.
40. In an electric switch, a pivoted actuating member, pivoted and cooperating contact members including a pivoted contact member movable about the pivot of said actuating member, means for interlocking said actuating member and pivoted contact member for movement about said pivot, and mechanism for actuating said 45 movable contact member upon actuation of said actuating member comprising cam means having a plurality of spaced cams and cooperating cam means engageable with said spaced cams, one of said cam means swinging with said actuating member and the other cam means being resiliently mounted to impart a snap action to 50 said movable contact member.
55. In an electric switch, a pivoted actuating member, pivoted and cooperating contact members including a pivoted contact member movable about the pivot of said actuating member, means for interlocking said actuating member and pivoted contact member for movement about said pivot, and mechanism for actuating said 60 movable contact member upon actuation of said actuating member comprising cam means having a plurality of spaced cams and cooperating cam means engageable with said spaced cams, one of said cam means swinging with said actuating member and the other cam means being 65 resiliently mounted to impart a snap action to said movable contact member, said pivoted con-

tact member being resilient and flexing toward and away from said actuating member while interlocked with said actuating member.

12. In an electric switch, a pivoted actuating member, pivoted and cooperating contact members including a pivoted contact member movable about the pivot of said actuating member, means for interlocking said actuating member and pivoted contact member for movement about said pivot, mechanism for actuating said movable 10 contact member upon actuation of said actuating member comprising cam means having a plurality of spaced cams and cooperating cam means engageable with said spaced cams, one of said cam means swinging with said actuating 15 member and the other cam means being resiliently mounted to impart a snap action to said movable contact member, a second contact member likewise movable about said pivot and actuated by said actuating mechanism, and cooperating 20 contact means engaged by said second contact member in a predetermined position of said first mentioned contact member.

13. A movable switch member for snap switches comprising a holder member movable 25 about a pivot and having an aperture therein, a pivoted switch actuating lever having a portion projecting into said aperture and thereby interlocked with said holder for joint movement therewith, and a pivoted contact member at one 30 side of said lever also having a portion projecting into said aperture and thereby interlocked with said holder for joint movement with the latter and said lever.

14. A movable switch member for snap 35 switches comprising a pivoted holder member having an aperture therein and also having cam means formed thereon, a pivoted switch actuating lever having a portion projecting into said aperture and thereby interlocked with said 40 holder for joint movement therewith, and a pivoted contact member located at one side of said lever and between the latter and the cam means of said holder member also having an interlocking portion projecting into said aperture and thereby interlocked with said holder for joint 45 movement with the latter and said lever.

15. A movable switch member for snap switches comprising a pivoted holder member having an aperture therein at one side of its 50 pivot, a switch actuating lever pivoted adjacent one end having a portion adjacent its pivoted end projecting into said aperture and thereby interlocked with said holder for joint movement therewith, said holder member also having cam 55 means disposed alongside said lever on the opposite side of its pivot from said projecting portion, and a pivoted contact member located between said lever and cam member and having a portion projecting into the aperture in said 60 holder member and thereby interlocked with the latter for joint movement with the latter and said lever and having a contact portion disposed between the cam means on said holder member and the free end of said lever.

JOHANN G. PETERSON.
